[57] ABSTRACT

Pencil apparatus comprising a translating member mounted within a flexible tubular pencil barrel adjacent one end of a stick of writing material longitudinally disposed in the barrel. The translating member is responsive to radial deformation forces applied to the pencil barrel to axially advance the writing stick through the barrel. Support members may be provided within the barrel to radially support the stick of writing material. An eraser may be provided which is also responsive to radial deformation forces applied to the pencil barrel to axially advance the eraser through the barrel, but in an opposite direction.

10 Claims, 5 Drawing Figures

PENCIL APPARATUS

CROSS-REFERENCE TO RELATED APPLICATION

The present application is a continuation-in-part of our copending application Ser. No. 238,326, filed Mar. 27, 1972, now issued as U.S. Pat. No. 3,806,262.

BACKGROUND OF THE INVENTION

1. Field of the Invention

The present invention pertains to apparatus for dispensing material from a tubular member. In particular, it concerns apparatus suitable for axially advancing a material through a tubular member for dispensing through one end thereof. More specifically, the present invention pertains to simplified translating apparatus suitable for feeding a pencil lead out the end of a pencil barrel.

2. Description of the Prior Art

Mechanical pencils have been known for many years. Such pencils eliminate the necessity of having to frequently sharpen the pencil as with the common wooden pencil. However, one disadvantage of the mechanical pencils heretofore developed is that they are relatively expensive in comparison with wooden pencils. Many attempts have been made to develop a simplified mechanical pencil which can compete with the less expensive wood pencils. Some of these designs may be seen by referring to the following U.S. Pat. No. 444,974 — Climenson, No. 605,657 — Toquet, No. 2,523,568 — Halverson and No. 2,563,551 — Refsdal. Although some of these designs are less expensive than some mechanical pencils, they are still more expensive than the common wooden pencil, and naturally, more complex.

In our aforementioned copending application, Ser. No. 238,326, a simplified translating mechanism is disclosed suitable for dispensing lead from a tubular pencil barrel in which the translating member is disposed. The translating member may comprise a central body portion from which a resilient portion projects radially for engagement with the internal walls of the tubular member. The tubular member is deformable on the application of external radial forces thereto to cause alternate deformation and restoration of the resilient portion of the translating member. The resilient portion can take the form of a frusto-conical skirt, a plurality of fingers, or other shapes, slanting in a rearwardly direction relative to the direction of desired axial advance. The unique shape of the translating member causes it to be advanced step-by-step on alternate deformation and restoration of the surrounding tubular member causing the lead or writing stick contained therein to be dispensed through one end of the tubular member.

The design concept for the mechanical pencil and the common wooden writing pencil have been relatively unchanged for many years. With such a translating mechanism, the same utility is provided with significant cost reduction. Accordingly, a mechanical pencil is provided which is simple to operate, very inexpensive to manufacture and safer than other mechanical pencils.

SUMMARY OF THE INVENTION

The present application is directed to improvements in pencil embodiments of the invention disclosed in our copending application Ser. No. 238,326. Like the former embodiment, the pencil of the present invention

comprises a flexible tubular barrel; a stick of writing material longitudinally disposed in the barrel; and resilient translating means engaging one end of the stick within the barrel, responsive to radial deformation forces applied thereto to axially advance the stick and translating means through the barrel, in one direction only.

In addition the pencil of the present invention comprises support members within the barrel having apertures through which the pencil stick passes so as to centrally support the stick or lead within the barrel. This reduces the possibility of breakage of the lead due to bending of the barrel or dropping of the pencil. These support members may take several forms.

15 An eraser may also be provided embodying the same principles as the translating means. It may have a cylindrical body adjacent to a frusto-conical skirt portion. The skirt portion is responsive to radial deformation forces to force the body portion, the end of which may be used to erase, out of the pencil barrel in a direction opposite to lead feeding.

20 Thus, the improved pencil is one which offers several unique advantages. It is simple to operate, inexpensive to manufacture, fascinating to the operator, durable and safe. In addition an eraser is provided which offers longer life than the ordinary pencil eraser. Other objects and advantages of the invention will be apparent from the accompanying drawings and description which follow.

30 BRIEF DESCRIPTION OF THE DRAWINGS

In the description which follows, reference will be made to the accompanying drawings in which:

35 FIG. 1 is a perspective view of a simplified mechanical pencil employing a translating mechanism and support members according to a preferred embodiment of the invention;

40 FIG. 2 is a cross-sectional view of another variation of the translating mechanism of the invention shown in a flexible tubular member which has been ovoided or deformed by pressing on opposite sides thereof;

45 FIG. 3, taken along line 3—3 of FIG. 2, is a longitudinal section of the deformed tubular and translating members of FIG. 2, taken along the minor diameter thereof;

50 FIG. 4, taken along line 4—4 of FIG. 2, is a longitudinal section similar to FIG. 3 except being taken along the major diameter thereof; and

55 FIG. 5 is a perspective view of the portion of a tubular member in which is disposed an eraser utilizing the principles of the translating mechanism of the present invention.

FIG. 6 is a perspective view of an alternative support member.

DESCRIPTION OF THE PREFERRED EMBODIMENTS

Referring first to FIG. 1, there is shown a tubular pencil barrel 10 in which is longitudinally disposed a writing stick or pencil lead 12. The pencil barrel 10 is provided with a frusto-conical tip 14 through the end of which is provided a cylindrical aperture or passage 16. The tip 14 can be separately manufactured of metal or any other suitable material. However, it can be integrally formed with the rest of the barrel 10. The barrel 10 is preferably of a flexible material such as plastic and may be formed by extruding. The pencil tip 14 can

also be provided with a countersunk frusto-conical funnel or guide cone 18 to facilitate feeding of lead through the aperture 16. The rearward end of the lead stick 12 is affixed to a translating mechanism 20 which is longitudinally disposed within the barrel 10.

Support members 11, 13 may also be provided within the barrel 10 to support the lead 12 against bending forces which might break the lead. These support members also cushion the lead against shock forces which might be encountered if the pencil were dropped.

Two types of support members are shown. The first 11 comprises a pair of wafer-like circular disks with central apertures through which the lead 12 may pass. The disks are hingedly connected at one side 11a to help prevent them from becoming cocked to one side within the barrel 10. The second type 13 comprises a square shaped wafer the corners 13a of which have been bent inwardly so that it may be accommodated within the tubular barrel 10. Either of these support members may be conveniently made of paper or many other suitable materials. Of course other designs might also be used.

The translating mechanism 20 can take several forms. The one shown in FIG. 1 has a cylindrical body portion at the forward end of which is a frusto-conical guide nose 22 and at the rearward end of which is a frusto-conical skirt portion 23. The diameter of the body portion 21 and the minor diameter of the frusto-conical skirt 23 is less than the internal diameter of the barrel 10. The major diameter of the frusto-conical skirt 23, in its free state, is greater than the internal diameter of barrel 10. The translating member 20 is of a resilient material, such as rubber, and when it is inserted into the pencil barrel 10 from the end opposite tip 14, the skirt 23 is compressed or deformed by the walls of the barrel 10. The rear end of translating member 20 may be countersunk or hollowed out such as shown at 25 to make the lip 27 at the base of skirt 23 more flexible.

By grasping the pencil barrel 10 near the translating mechanism 20 and applying an external force thereto, by finger pressure, the barrel will be deformed so that its cross section at that point has an oval shape such as the barrel 30 shown in FIG. 2. When the barrel 10 is deformed, a portion of the skirt member 23 is deformed or flexed inwardly. When the barrel is released, its circular cross section is restored. During the release, the deformed portion of the skirt 23 expands. However, since the skirt 23 flares rearwardly, it resists movement in the rearward direction. Thus, the expansion of the skirt, or return to its initial position, exerts a force in the forward axial direction, causing the body portion 21 and consequently lead stick 12 to be advanced a short distance. Radial forces can be alternately applied to and released from the barrel or, preferably, the barrel can be rolled between the fingers to repeat the cycle.

Referring now to FIGS. 2-4, another embodiment of the invention will be shown which will further illustrate the step-by-step advancing concept utilized in the invention. The translating mechanism 40 of this particular embodiment is shown disposed in a flexible tubular member 30, such as the barrel 10 in FIG. 1. It also comprises a central body portion 41. However, instead of a frusto-conical skirt, such as 23 in FIG. 1, a plurality of resilient fingers 43 project radially therefrom for contact with the tubular body 30 in much the same

manner as the frusto-conical skirt 23 of FIG. 1. In the illustration shown, there are two sets of four fingers each oriented at 90° to each other. The translating mechanism 40 is placed inside the tubular body 30, which has a diameter slightly less than the diameter of a circle enclosing the tips of fingers 43 in their free standing position. Ovaling the body 30, around the translating member 40, increases the preload and grip of the fingers 43 on the minor axis while relieving the preload on the major axis, allowing the fingers 43 on the major axis to spring forward and outward, as shown in FIG. 4. Restoring the tube to its nondeformed shape, causes the extended fingers 43 to grip the body walls, preventing backward motion and pulling the other fingers 43 forward along the central body portion 40.

The amount of advance of the translating member per actuation is proportional to the amount of finger or skirt deformation, the diameter of the translating member and friction between the translating member and tubular bore. The travel obtained in one actuation may be illustrated by the distance "x" as shown in FIG. 3.

The shape of the elastic tubular member in which the translating member is disposed can be of any axisymmetric configuration as long as it can be significantly deformed without permanent set. There are, of course, a number of translating member shapes which will also function. Conical frustums such as shown in FIG. 1 and angled fingers or wires such as shown in FIGS. 2-4 can be used individually or in many combinations.

As shown in FIG. 5, the non-writing end of the pencil could be provided with an eraser 50 utilizing the same translating principles of the translating members 20 and 40 heretofore described. Such an eraser 50 might include a cylindrical body portion 51 and a frusto-conical skirt portion 52. The diameter of the body portion 51 and the minor diameter of the skirt portion 52 would be equal to or slightly less than the internal diameter of barrel 10. The major diameter of the frusto-conical skirt 52, in its free state, would be greater than the internal diameter of barrel 10.

As in the translating members 20 and 40, radial forces could be applied around the exterior of barrel 10 near skirt 52 by rolling the barrel 10 between the fingers. Alternate contraction and expansion of the skirt portion 52 would gradually feed the eraser 50 out of the end of barrel 10. This would permit continuous, replacement of eraser material, something not permissible with the standard wooden pencil. It will be noted that advance of the eraser 50 would be opposite to the direction of lead advancement in the pencil.

By selecting the proper barrel or tube material, a pencil embodying the present invention can be much safer than other mechanical pencils. The material selected can be adequately stiff for normal handling and use yet soft enough to collapse if struck sharply (as with a child falling on the pencil). During the collapse of the barrel, the lead stick will break harmlessly within the barrel.

The unique translating mechanism disclosed herein can be used, of course, not only with pencils, but in any other application which requires the dispensing of a material from a tubular container. For example, it is ideally suited for dispensers for lubricants, adhesives, medicines, drugs, cosmetics, etc. The common lipstick or lip balm would be ideally suited for such a mechanism.

Components of a pencil or dispenser may, according to the present invention, all be made from plastic, rubber, etc., which are materials amenable to mass production at very low unit cost. There are no close tolerance parts and the materials are not critical. The tubular body can be a simple extrusion of elastic material such as plastic, metal, rubber, etc. The translating mechanism or piston can be an injection molded part or machined from similar elastic material. The unique mechanism of the invention utilizes very simple components.

Although only a few embodiments of the invention have been described herein, several applications thereof have been mentioned. Many other variations of construction and applications will be apparent to those skilled in the art. It is therefore intended that the scope of the invention be limited only by the claims which follow.

We claim:

1. A pencil comprising: a flexible tubular barrel; a 20 stick of writing material longitudinally disposed in said barrel; support means within said barrel centrally supporting said stick of writing material therein; and resilient translating means engaging said stick within said barrel responsive to radial deformation forces applied to said barrel around said translating means to axially advance said stick and said translating means through said barrel in one direction only.

2. A pencil as set forth in claim 1 in which said support means comprises a wafer-like member, between said translating means and the end of said barrel, having a central aperture through which said stick of writing material passes.

3. A pencil as set forth in claim 2 in which said support means comprises a pair of said wafer-like members hingedly connected on one side thereof to prevent cocking within said barrel.

4. A pencil as set forth in claim 2 in which said wafer-like member is polygonal in shape, the corners of which are bent inwardly to permit accommodation of said member within said barrel.

5. A pencil as set forth in claim 1 in which said support means slidably engages the walls of said barrel member preventing interference with the advancement of said translating means through said barrel.

6. A pencil as set forth in claim 1 including an eraser disposed in one end of said barrel comprising a cylindrical body portion and an adjacent portion from which radially projects projection means for engagement with the internal walls of said tubular member, said projection means being responsive to radial deformation forces applied to said barrel around said eraser to axially advance said eraser through said barrel in a direction opposite to said one direction.

7. A pencil comprising: a flexible tubular barrel; a 15 stick of writing material longitudinally disposed in said barrel; resilient translating means engaging said stick within said barrel responsive to radial deformation forces applied to said barrel around said translating means to axially advance said stick through said barrel; and an eraser disposed in one end of said barrel responsive to radial deformation forces applied to said barrel around said eraser to axially advance said eraser through said barrel in a direction opposite the advance of said stick.

8. A pencil as set forth in claim 7 in which said eraser comprises a cylindrical body portion from which radially projects resilient means for engagement with the interior of said barrel.

9. A pencil as set forth in claim 8 in which said resilient means comprises a frusto-conical skirt converging toward the direction of said eraser axial advance, the major diameter of said skirt being greater than the internal diameter of said barrel.

10. A pencil as set forth in claim 9 including support means disposed within said barrel between said translating means and the end of said pencil opposite to said one end, said support means having an aperture through which said stick passes for central radial support thereof within said barrel.
